PLASTER APPLICATOR

Paul H. Sommers, Montgomery, Ala.

Application May 25, 1949, Serial No. 95,297

1 Claim. (Cl. 72—130)

1

The present invention relates to the art of plastering, and is concerned with the provision of a mechanical aid to facilitate the application of a coating or layer of plaster to a wall. When I speak of "plaster" herein, I do not use the term in a restrictive sense, but intend to include such plastic self-setting materials as stucco, mortars, cements, and the like. The device may be employed for applying plastic material which is not self-setting, but in the building trades self-setting plastics are the usual ones employed. The term "mortar" is used interchangeably with "plaster" except as the context indicates otherwise. I use the term "wall" to designate a supporting surface in any position, and of any usual contour that may be encountered in the building trades.

The spreading of a mass of plastic material, such as plaster, upon a surface, such as the wall of a building, calls for considerable skill, and involves a good many motions.

After a batch of plaster is prepared, a limited supply thereof is transferred to a hawk held in one hand of the artisan, which hawk serves as a support for said limited supply of plaster, and as a means for feeding small amounts of said supply to a trowel in the other hand of the workman. The trowel with its burden is then applied to the surface to be coated, and the charge or burden carried by the trowel is simultaneously spread out into a film and pressed against the supporting surface to secure adhesion which may involve partial penetration of the supporting wall, particularly where lath, plasterboard, expanded metal and the like are employed to support the plaster. Then the trowel is applied to smooth the surface and to some degree to equalize the thickness of the film over the area covered.

To convert a lump or mass of relatively soft plaster into a film is not per se a difficult matter. Children do that in making mudpies. But to cover an area with a reasonably uniform film by repeated applications of masses or lumps and trowelling them out into a continuous film, particularly upon a foraminous support such as lath, expanded metal or the like, gives opportunity for error at each application of an additional mass or lump. To smooth out the result of applying each mass or lump similarly gives opportunity for error as it may result in excessive penetration of the foraminous support and too thin a coating on the exposed surface, or it may result in too great thinning out laterally of the plaster applied. It is in successfully bypassing these opportunities for error that the skill of the artisan reveals itself.

2

In addition to the above requirements for skill, the operations of repeatedly adding small increments and flattening them into a continuous film or layer appears to me to involve a large number of motions which could be avoided by some more general action or motion which would combine the effects of a great many of them.

It occurred to me that it might be possible to develop a mechanical device which would, in its structure and mode of operation, avoid or eliminate some of the opportunities for error now calling for the exercise of skill and judgment. By building the skill into the machine as it were, I would remove the need for at least a substantial part of the skilled operations required by present practice by substituting the simpler manipulation of the machine itself.

I conceived that the intermittent operation of applying and trowelling small increments might be combined into an action characterized by continuity. I conceived that the critical problem of gauging the uniformity of film depth might be combined with the continuous feeding and trowelling, and that a relatively large amount of plaster could be thus handled and applied all at one operation.

I am aware that magazine tools and devices for continuous feeding of a plastic material are old, but, so far as I am informed, no satisfactory device of general utility in the art of plastering has been evolved. This is, I believe, chiefly because no device has actually performed the interrelated functions of continuously supplying the plaster, feeding it out through a metering opening, gauging the proper depth of layer deposited, and trowelling the layer to secure the desired penetration at the inner surface and smoothness on the outer surface, which my device performs.

A further object of my invention is to provide a device which, while relieving the operator of the necessity for exercising skill, will itself be of simple construction, low cost, and inherently simple to operate for the various functions to be performed by it.

In the preferred form of my invention, I provide the combination of a mortar storage chamber or magazine, a regulating depth guide and a screed with trowelling action to apply a uniform layer of mortar on any surface to which the material is to be applied. Rapid loading of the chamber is possible by simply reversing the position of the device and scooping up a supply. The need for the hawk and trowel for the application of plaster, stucco, mortar and the like, in all planes, is eliminated by the device of my

invention. The trowel may, of course, be used to the extent needed to correct surface defects.

Relieving the operator of the necessity for exercising a high degree of skill or judgment permits on the one hand an unskilled operator to perform an acceptable job of plastering, and on the other hand, it permits of a vastly greater output, and in the case of a skilled operator, relieves him of the necessity for exercise of judgment, and in either case permits of the attainment of a vastly greater output for the same amount of exertion or within a given period of time.

Now in order to acquaint those skilled in the art with the manner of constructing and operating a device embodying my invention, I shall describe, in connection with the accompanying drawings, a preferred embodiment of the invention and its structure and mode of use.

In the drawings:

Figure 1 is an isometric view of an embodiment of my invention held in the position in which it is used in applying plaster to a vertical wall;

Figure 2 is a similar isometric view of a form of applicator for applying plaster to a ceiling or other horizontal wall, as well as to a vertical wall;

Figure 3 is a diagram illustrating the method of charging the magazine when the device is in loading position.

Figure 4 is a similar diagram showing the device of Figure 1 in a carrying position when it is loaded.

Figure 5 is a diagram of the device of Figure 1, illustrating the method of placing the applicator in position to apply plaster to a vertical wall;

Figure 6 is a similar diagram showing the device applying mortar to the vertical wall;

Figures 7 to 10 are diagrams of the mode of use of the device of Figure 2;

Figure 7 shows the device of Figure 2 being loaded with mortar or plaster;

Figure 8 shows the device loaded and then being disposed in carrying position;

Figure 9 shows the device as being brought into position to apply plaster to a horizontal wall;

Figure 10 shows the operation of applying plaster to the ceiling or other horizontal wall; and

Figure 11 is an isometric view, similar to Figure 1, showing the disposal of a mechanical or electrical vibrator unit on the magazine to assist in handling stiff mortars or plastic materials, and trowelling the same upon a wall.

Like reference characters indicate like parts throughout.

The device shown in Figure 1 comprises essentially a magazine portion 1, runners 2, 2 which form depth gauges for the layer to be applied, a throat plate 3 which forms with the runners 2 a throat or screed to measure out and squeeze against the surface a sheet of the plastic being applied, a flexible trowelling margin or edge 4 for trowelling the layer of plastic deposited, and handles by means of which the device may be manipulated. The throat plate 3 is preferably set at a slight angle to the plane determined by the edges of the runners 2, 2, so that the resulting throat is tapered and tends to exert pressure of the sheet of plastic against the wall to which it is applied. The handles comprise a handle 5 for supporting the magazine end of the device, and a handle 6 for supporting the trowelling end of the device and for applying trowelling pressure to the flexible blade 4.

The magazine 1 is generally boxlike in character, resembling a flat rectangular sheet metal box

with the open end truncated or cut on a diagonal plane which may be approximately 45° to the longitudinal axis of the box. As shown in Figure 1, the end closure wall 7 which becomes the bottom wall when the device is carried loaded, as shown in Figure 4, is joined to the top or loading wall 8, and the bottom or outlet wall 9 and the two side walls 10, 10, which latter are alike in size and outline. The loading wall 8, which is normally uppermost when the device is used for applying plaster to the wall, is shorter than the outlet wall 9 which is lowermost when the device is in position for applying plaster to a wall. The walls of the device are preferably formed of sheet metal, being generally rectangular in outline, and of appropriate dimensions. In an embodiment which I have successfully operated, the loading wall is approximately 8 inches from the loading edge to the end closure, and approximately 12 inches in width along the loading edge. The feeding wall 9 is of the same width as the loading wall and is of greater length, namely, approximately 12 inches. The throat plate is of approximately three inches in length along the line of flow of the material, and the trowelling plate extends approximately 1 1/4 inches beyond the throat line and terminates in a free flexible edge. The trowelling plate is preferably made of stainless steel sheet approximately $25/1000$ " thick.

These dimensions are given by way of exemplification and not of limitation. The handle 5 at the rear of the device is connected to two upright posts 12, 12 which are welded to a reinforcing strap 13 mounted preferably at the rear edge of the bottom or feeding plate 9.

A reinforcing frame made of thin strap stock comprises the side bars 14, 14 secured to the margins of the diagonal edges of the plates 10, 10, and these side bars 14, 14 are joined at the bottom edge of the throat plate 3, as viewed in Figure 1, by the cross bar 15 of angular cross section. Posts 16, 16 secured to the angle bar 15, as by welding, support the hand grip 6 at the trowelling end of the device. The side edges of the sheet metal throat plate 3 may be bent up at right angles to the plane of the plate 3, and clamped between the runners 2 and the side bars 14 for supporting rigidly the edges of the throat plate 3 and the front margin of the throat plate 3 may likewise be bent up at right angles, and folded up flat against the lower leg of the angle bar 15 and secured thereto to reinforce the forward edge of the throat plate. The trowelling plate, of which the free flexible edge acts to form a smooth surface of the coating, is secured to the inside face of the throat plate 3 by suitable screws or rivets, preferably leaving a flush surface for ease in travel over the surface of the layer of plaster.

The depth gauges or runners 2, 2 are mounted adjustably by screws 17 threaded into the side plates 14, 14 and extending through slots 18, 18, whereby the runners 2, 2 may be adjusted for controlling the depth of layer applied to the wall or surface.

The mode of use of the device of Figure 1 is illustrated in Figures 3, 4, 5 and 6.

The loading of the device is illustrated in Figure 3. A pile of mortar or plaster is deposited on a supporting surface 20, which may be either a mortar board or the mortar box or the like. The device is grasped by the hands 5 and 6 with the loading wall 8 disposed substantially flat on the supporting surface 20, and the open end of the device is shoved into the pile of mortar

until the chamber is loaded. Thus, by merely inverting the device, and shoving it into the pile of mortar, a charge of mortar may be picked up with minimum time and effort. The device is then swung into the position shown in Figure 4 with the handle 6 and the open end uppermost, and the device carried to the point of use. The wall 21, shown in Figure 5, to which a layer of plaster is to be applied, may be any suitable surface, such as lath, expanded metal, 10 screen, plasterboard, tile or the like, which is customarily subject to the application of plaster.

In modern practice, the plaster is generally applied to metal lath or to plaster board. Plaster board is supplied in two common forms; one form consists of plain gypsum board covered with a layer of absorbent paper and provided with rounded edges. The other form consists of gypsum board covered with an absorbent paper and having a pattern of holes of approximately one inch in diameter punched through the body. In either structure, adhesion of the plaster to the board is secured through the absorbent paper. In the first example, bond and adhesion are assisted by forcing the plaster into the openings and recesses formed at the junctions of the edges and at the rounded corners. In the second example, the extrusion of the plaster through the openings locks the plaster to the board.

Figure 5 shows the device being raised into position by applying the trowel 4 at the point where the previous application has deposited the layer of plaster 22, and the device is swung upwardly in the direction of the arrow into the dotted line position where the runners bear fully and evenly upon the supporting surface. The device is then stroked upwardly as shown in Figure 6. The mortar flows down the outlet wall 9 between the throat plate 3 and the wall, and is finally engaged by the flexible trowel portion 4, which smooths and presses to a uniform depth the layer of mortar applied.

The throat defined by throat plate 3, the side runners 2, 2 and the wall surface 21 is preferably tapered at a low angle to develop pressure of the plaster against the surface of the wall as the material flows out of the reservoir and spreads on the wall. The angle of this plate relative to the wall may be adjusted to secure greater or less wedging action upon the plastic. The operator may apply greater or less pressure upon the flexible trowel plate 4 by rocking the entire device about the forward ends of the depth guide runners 2-2 while the said runners are in engagement with the wall surface being operated upon. Cement mortars are rather low in plasticity, as compared to lime mortars or plasterers, which characteristic makes them more difficult to apply, particularly to a vertical wall or to a ceiling. Hence, considerable pressure is desirable to press the material against the wall for attaining maximum density and to secure the desired adhesion and bonding. The taper of the throat assists in developing the desired pressure. Sufficient adjustment of the angle of the throat relative to the wall may generally be made merely by tilting the runners 2, 2 on the frame, since the flexible troweling plate will accommodate itself to the same by its flexibility.

The longitudinal axis of the device is at approximately 45° to the vertical wall 21 in the application of the mortar to the wall. The mortar usually is sufficiently free flowing that it will gravitate readily into the confined space between the guide runners and the throat plate, 75

pass through the tapered throat and be engaged by the trowel portion 4. If particularly stiff mortar is used, then a mechanical or electrical vibrator 23 attached to the bottom wall 9, as shown in Figure 11, may be employed. The device of Figure 11 with the electrical vibrator 23 is otherwise substantially identical with the device shown in Figure 1. Such a vibrator is well known. It consists of a rotating shaft with an eccentrically carried weight. Other means for developing a vibration or shaking action may be used.

The guides or runners 2, 2 may be adjusted for depth of layer, as previously explained, and they may be adjusted to apply a skim coating, as for finishing the surface of rough plaster.

The device of Figure 2, which is designed for application of plaster to a horizontal wall, such as a ceiling, differs from the device shown in Figure 1 in having provision for a movable end closure for the magazine 1 by which the mortar may be expelled therefrom. Otherwise it is like the device of Figure 1.

In the use of the device of Figure 2, the magazine will extend diagonally downwardly at a 45° angle to the ceiling, and it is necessary that the mortar be raised into the throat to secure the deposit of the desired layer. The outer margins or ends of the walls 8, 9, 10, 10, which form the boxlike magazine, are supported by an angle iron frame 25 for stiffening the end of the box magazine, and for forming a support and guide for the rods 26, 26 upon which the piston or plunger 27 in the box is carried. The piston 27 is rectangular in outline, and fits closely inside of the box, so that it acts as a movable wall for expelling the mortar in the magazine. The rods 26, 26 are guided in tubular guides 28, 28, which in turn are supported in cross bars 29, 29, attached to the angle iron frame 25. The two rods or plungers 26, 26 are joined at their outer ends by a hand grip 30 for operating the piston 27. The mode of use of the device of Figure 2 is illustrated in the diagrams of Figures 7 to 10.

To prepare the device for loading, the handle 30 is pulled outwardly, so as to bring the piston 27 to its outward position. Thereupon the device is laid flat on the loading surface 20 as shown in Figure 3. A charge of mortar is scooped up by moving the device, as illustrated in Figure 7, and the device is upended as illustrated in Figure 8 to carry the same to the point of use. Then, as shown in Figure 9, the flexible trowelling edge 4 is applied to the margin of the previous layer of mortar 32. The device is swung upwardly to bring the runners into engagement with the surface 31, as shown in the dotted line position in Figure 9. Thereupon, as shown in Figure 10, pressure is applied to the handle 30 to expel the mortar into the throat as the discharge end of the device is held up with the runners against the ceiling surface by means of the handle 6. With the two hands the device is then stroked towards the left as viewed in Figure 10, discharging mortar and trowelling the surface thereof in substantially the same manner as illustrated previously in Figure 6.

From the foregoing it will be apparent that my invention provides a simple, inexpensive mechanical aid for permitting the rapid and satisfactory application of mortar to a wall surface by one lacking the skill of the artisan. Alternatively, a skilled artisan with the use of my device may greatly increase his output and lessen the effort of the work. The device facilitates the continu-

ous feeding of a plastic material through the ~~end~~ and joining the loading wall and the outlet wall, metering throat defined by the throat plate 3 and the said side walls at said open end of the magazine, the guides or runners 2, 2, and the wall surfaces, ~~and~~ having parallel extensions beyond the adjacent The depth of the layer is properly gauged, a uniform pressure is applied, and the surface is ~~smooth~~ ⁵ said extensions constituting depth guides or runners for determining the depth of plaster to be deposited, and a flat flexible troweling plate having its rear edge connected to the outlet wall at said open end of the magazine and extending forwardly beyond said parallel runners and being free at its front and side edges to bear yieldingly upon the plaster which issues from the open end of the magazine between said depth guides, said trowelling plate lying in a plane substantially except as they are made essential by the appended ¹⁰ ~~15~~ parallel to the first said plane.

Variations of the specific structure will be made by those skilled in the art, and I do not intend to be limited to the details shown or described, the trowelling plate lying in a plane substantially except as they are made essential by the appended ¹⁰ ~~15~~ parallel to the first said plane.

PAUL H. SOMMERS.

I claim:

In a device of the class described, a substantially rectangular boxlike magazine for plaster open at one end only, said magazine comprising an outlet wall and a loading wall, said walls being substantially parallel to each other, the outlet wall being longer than the loading wall, and the edges of said two walls at the open end of the magazine lying substantially in a plane diagonal ²⁵ to the longitudinal axis of said magazine, said magazine also comprising an end wall, and two side walls substantially parallel to each other
